TOOL TRAY FOR MACHINE TOOLS

Herbert W. Westberg, 2459 Huntington Turnpike,
Trumbull, Conn.

Filed May 14, 1964, Ser. No. 79,985

Term of patent 7 years

(Cl. D55—1)

FIG. 1 is a front elevation of a tool tray for machine tools, showing my new design;

FIG. 2 is a side elevation;

FIG. 3 is a top plan view;

FIG. 4 is a rear elevation; and

FIG. 5 is a perspective view.

The broken lines are shown for illustrative purposes only, and the undisclosed side of the article is substantially the same as the side shown except for the omission of the bracket member, as indicated on the drawing.

I claim:

The ornamental design for a tool tray for machine tools, substantially as shown and described.
